(57) **CLAIM**

The ornamental design for a transfer robot, as shown and described.

DESCRIPTION

Transfer robot

Fig. 2.1 is front elevation view of a transfer robot showing our new design;

Fig. 2.2 is a back elevation view thereof;

Fig. 2.3 is a left-side elevation view thereof;

Fig. 2.4 is a right-side elevation view thereof;

Fig. 2.5 is a top plan view thereof;

Fig. 2.6 is a bottom plan view thereof;

Fig. 2.7 is a perspective view showing a retracted state thereof;

Fig. 2.8 is a perspective view thereof;

Fig. 2.9 is a perspective view thereof;

Fig. 2.10 is an enlarged view of detail 2.10 in FIG. 2.8;

Fig. 2.11 is an enlarged view of detail 2.11 in FIG. 2.8; and

Fig. 2.12 is an enlarged view of detail 2.12 in FIG. 2.9.

The product is used to transfer objects.

The broken (dashed) lines show portions of the transfer robot that form no part of the claimed design. The dot-dashed broken line in FIGS. 2.8-2.12 shows the boundary of the enlarged views and forms no part of the claimed design.
